ENVELOPE

Eugene F. Ahlquist, Minneapolis, Minn.

Application December 21, 1931, Serial No. 582,374

2 Claims. (Cl. 229—80)

This invention relates to new and useful improvements in envelopes, and an object of the invention is to provide an envelope having means embodied in the construction thereof whereby, when the envelope has once been sealed, it cannot be opened and resealed without defacing or mutilating it so that the receiver may note, at a glance, that the envelope has been tampered with by an unauthorized person.

10 A further object is to provide an envelope comprising a body portion having an opening and a flap adapted to form a closure for said opening, said flap being gummed whereby it may be secured to the body portion of the envelope to seal said opening, and a portion of the gummed portion of said flap being treated in such a manner as to break down the fibers, or weaken the material thereof, whereby the flap cannot be opened without defacing or mutilating it.

20 A further object is to provide an envelope comprising a flap adapted to provide a closure for the usual opening thereof, and a portion of the flap being treated in such a manner as to weaken a portion of the material thereof, as for example, by subjecting it to high pressure, or by closely perforating a portion of the flap, or by subjecting a portion of the flap to heat, or to the action of chemicals, whereby the fibers are weakened to the extent that the flap cannot be opened, after it has once been secured to the body of the envelope, without tearing or otherwise mutilating it.

30 Other objects of the invention will appear from the following description and accompanying drawings and will be pointed out in the annexed claims.

35 In the accompanying drawings there has been disclosed a structure designed to carry out the various objects of the invention, but it is to be understood that the invention is not confined to the exact features shown, as various changes may be made within the scope of the claims which follow.

In the drawings:

40 Figure 1 is a view showing an envelope with the invention embodied in the construction thereof and showing the flap in open unsealed position;

45 Figure 2 is a view showing the flap sealed and the portions of the flap which have been treated in accordance with the invention;

50 Figure 3 is a view similar to Figure 2 showing an instrument inserted under the flap to open it, and also showing the treated portion of the flap torn or mutilated by the instrument;

55 Figure 4 is a view showing an envelope having a

portion of its flap treated substantially the full length thereof;

60 Figure 5 is a similar view showing an instrument inserted under the weakened flap and indicating how it is mutilated thereby;

65 Figure 6 is a view showing a portion of an envelope having its flap provided with a plurality of closely disposed perforations for the purpose of weakening it; and

70 Figure 7 is a view showing a portion of a sealed envelope with a separate seal secured to the flap thereof.

75 In the selected embodiment of the invention here shown, for purposes of disclosure, there is illustrated in Figure 1, an envelope comprising 70 end flaps 2 and 3 and a bottom flap 4 folded, one over the other, and suitably secured together to provide the body of the envelope. The broken line 5 indicates where the top flap 6 is folded to close and seal the envelope, as shown in Figures 75 2 and 3. It will be noted that the upper edges of the end flaps extend above the fold line 5 so that when the top flap 6 is folded against the envelope body and sealed, it will be impossible for a person to insert an instrument into the 80 interior of the envelope body without damaging the walls thereof or breaking the seal of the envelope.

85 An important feature of this invention resides in treating portions of the flap 6 in such a manner that when once it has been sealed, it cannot be opened and resealed without being so marked that the recipient of the letter or envelope may readily note that it has been tampered with.

90 To thus treat the flap 6, I have shown in Figures 1 to 3, circular portions 7—7 and 8 thereof which have been treated in a manner to cause the fibers of the material to become weakened so that when the flap is secured to the body portion of the envelope, as shown in Figures 2 95 and 3, by the gum or adhesive usually provided upon the flap, it cannot be reopened without tearing or mutilating the flap. This may be accomplished in various ways as, for example, by subjecting the treated portions of the flap to 100 heat, or high pressure, or to the action of certain acids or chemicals.

105 Preferably, only portions of the gummed portion of the flap are treated as shown in Figures 1 and 3, so that when the flap is sealed, the 105 weakened portions thereof will not be of sufficient magnitude to weaken the seal. By treating portions of the flap as shown in Figures 2 and 3, when a letter opener or other suitable instrument is inserted under the sealed flap 6, 110

and it contacts with one of the treated portions 7 or 8 of the flap, these portions will be destroyed as shown at the left hand side of Figure 3, because of the frail and weakened condition 5 of said treated portions, and because they are secured to the envelope body in the same manner as the flap.

By thus treating portions of the flap, the usual metallic seals or locks now commonly used on 10 various types of commercial envelopes may be dispensed with. Metallic locks and seals add considerably to the manufacturing cost of the envelopes, and are usually more or less bulky 15 and are therefore objectionable. By treating portions of the flap as disclosed in this invention, the envelope when sealed is rendered substantially as secure as if metallic locks or seals were used for the reason that the flap, when once secured to the body portion, cannot be opened 20 and resealed without leaving a mark which may be quickly noted by the recipient of the envelope. Also, by treating the flaps as herein disclosed, very little is added to the manufacturing 25 cost, thereby providing such an article embodying all of the advantages of the metallic seals or locks now used and, at the same time, considerably reducing the cost of the article and facilitating the operation of closing and sealing the envelope.

30 In the manufacture of the envelopes, I have found that by applying heat to the portions 7—7 and 8 of the flap by means of suitable dies, the flap may be treated without materially adding to the cost of manufacture, and also when using 35 heat, suitable information may be impressed in the treated portions of the envelope such, for example, as advertising matter and a return address.

In Figures 4 and 5, I have illustrated an envelope body 9 having a flap 10, the lower marginal 40

edge portion 11 of which is treated as above described so that when an attempt is made to open the envelope with an instrument 12, after once the flap 10 has been sealed, the flap will become damaged or defaced to the extent that it may be quickly noted by the recipient, as clearly illustrated in Figure 5.

80 Figure 6 shows another method of treating a portion of the flap to weaken it by providing therein a series of closely disposed perforations 13. When the flap is thus treated, it cannot readily be opened without tearing the perforated portion of the flap so that if an attempt to open the sealed envelope is made by an unauthorized person, it may be quickly noted.

85 In some cases, it may be found desirable, in lieu of treating portions of the flap as above described, to affix an individual seal 14 to the sealed envelope flap, as shown in Figure 7, which seal has been previously treated to render it 90 weak and frail, so that the flap cannot be opened without tearing or destroying said seal.

95 I claim as my invention:

1. An envelope comprising a body portion having an opening therein and a gummed flap for 100 closing said opening, and portions of the gummed portion of said flap being heat-treated to break down and weaken the fibers thereof so that the flap cannot be opened without tearing or mutilating said weakened portions.

105 2. An envelope comprising a body portion having an opening therein and a gummed flap for closing said opening, and a portion of said flap adjacent its free edge and extending substantially the entire length thereof being subjected to the 110 action of heat, thereby to break down and weaken the fibers thereof whereby the flap cannot be opened without tearing or mutilating said weakened portion.
